UNITED STATES PATENT OFFICE

MORRIS H. ANDERSON, OF DWIGHT, ILLINOIS

SAFETY CAGE FOR BANKS

Application filed January 3, 1930. Serial No. 418,284.

This invention aims to provide novel means whereby a person intending to burglarize a bank may be trapped and held until the police authorities come to take him away.

5 It is within the province of the disclosure to improve generally and to enhance the utility of devices of that sort to which the present invention appertains.

With the above and other objects in view, 10 which will appear as the description proceeds, the invention resides in the combination and arrangement of parts and in the details of construction hereinafter described and claimed, it being understood that changes may 15 be made in the precise embodiment of the invention herein disclosed, within the scope of what is claimed, without departing from the spirit of the invention.

In the accompanying drawings:

20 Figure 1 shows in front elevation, a device constructed in accordance with the invention;

Figure 2 is a vertical transverse section;

Figure 3 is a vertical transverse section at right angles to Figure 2;

25 Figure 4 is a horizontal transverse section on the line 4—4 of Figure 1;

Figure 5 is a fragmental vertical section on the line 5—5 of Figure 1;

Figure 6 is a transverse horizontal section 30 on the line 6—6 of Figure 1;

Figure 7 is a fragmental section on the line 7—7 of Figure 6;

Figure 8 is an elevation of the cashier's lever.

35 In carrying out the invention, there is provided a box-like open work frame 1, which may be made in various ways without jeopardizing the utility of the invention. Parts of the frame 1 which have especial functions will be alluded to particularly. The frame 1 comprises vertical rods 32. Between certain of these rods there is a space at the front of the frame (Figure 1) which forms a doorway 2. The frame 1 embodies a base 3.

40 At the corners of the base 3 (Figures 7 and 4) are located supports 4, in the form of rods, which are slidably adjustable in the base 3, in the direction of their length. Nuts 5 are threaded on the supports 4 and cooperate with the base 3 to hold the supports 4 in any posi-

tion to which they may have been adjusted lengthwise. Rollers 6 are mounted on the inner ends of the supports 4 and cooperate with a track 7 on the lower end of a cage 8. It may now be stated that the supports 4 are adjusted lengthwise through the instrumentality of the nuts 5, in order that the rollers 6 may cooperate with the track 7 and keep the cage 8 centered for rotation about a vertical axis.

45 A hollow shaft 15 is secured at 39 (Figure 3) to the upper end of the cage 8. The shaft 15 turns in a lower bearing 16 carried by a spider 17 forming part of the frame 1. The shaft 15 turns, also, in an upper spider 18 constituting part of the frame 1. A head 19 is detachably secured to the upper portion of the shaft 15 and cooperates with the upper spider 18 to suspend the cage 8 for rotation about a vertical axis, the cage being centered, as has been explained hereinbefore, by means 50 of the rollers 6.

55 The cage 8 is provided on its inside with handles 9 whereby the cage may be rotated. The cage 8 has a doorway 10 which may be brought into registration with the doorway 2 of the frame 1, as shown in Figure 1 of the drawings. When the cage is rotated, the doorway 10 of the cage may be brought into registration with a window 11 in a shield 12 extended part way around the cage 8 and carried by certain of the vertical bars 32 that form parts of the frame 1. The window 11 in the shield 12 is located diametrically opposite to the doorway 2 in the frame 1. A cashier's shelf 14 (Figure 2) is located at the window 11 in the shield 12.

60 Within the hollow shaft 15 is located an insulating tube 20. The tube 20 is disposed below an inverted U-shaped member 21 that forms part of the frame 1. Conductors 24 extend downwardly through the insulating tube 20, and support a lamp 25 that is located at the lower end of the hollow shaft 15, as shown clearly in Figure 3 of the drawings.

65 The top of the cage 8 is formed by a ratchet wheel 22 connected by brackets 31 (Figure 2) with the upper end of the cage 8. The frame 1 carries resilient back stop pawls 23 (Figure 4) adapted to cooperate with the ratchet wheel 22. A latch 26 is mounted at one end 70

on one of the rods 32 of the frame 1 (Figure 5). On the ratchet wheel 22 are stops 27 wherewith the latch 26 is adapted to cooperate, at its inner end, as shown in Figure 5 of the drawings.

5 A vertical plunger 28 is pivoted at its lower end, as shown at 29, to the inner end of the latch 26. The plunger 28 is mounted for vertical sliding movement in a guide frame 10 30 carried by the spider 17. A compression spring 33 surrounds the plunger 28. The spring 33 has an upward thrust against the spider 17, and a downward thrust upon the plunger 28, so as to hold the latch 26 normally 15 in the path of the stops 27 on the ratchet wheel 22 that forms the top of the cage 8.

The lower end of a flexible element 34 is connected to the plunger 28. The flexible element 34 is extended horizontally, and 20 downwardly, over pulleys 35 journaled on the frame 1. The lower end of the flexible element 34 is connected to a pedal lever 36 (Figures 2 and 8), the pedal lever being located within ready access to the cashier who 25 stands within the bank at the shelf 14. The pedal lever 34 is fulcrumed at 37 on a bracket secured to a base plate 40 that carries a keeper 38.

In practical operation, the pedal lever 36 30 is engaged beneath the keeper 38, as shown in Figure 8. A pull then is put on the flexible element 34, and the flexible element 34 raises the plunger 28, the plunger 28 raising the latch 26, against the action of the spring 33, so that the latch 26 is out of the way of the stops 27 on the ratchet wheel 22 which forms the top of the cage 8.

The cage 8, now, is free for rotation.

The person having business at the bank 40 walks through the doorways 2 and 10 of Figure 1, into the cage 8. He then rotates the cage through the instrumentality of the handles 9 until the doorway 10 of the cage has moved through an arc of 180°, the doorway 45 10 of the cage then being in registration with the window 11 of the shield 12. When the doorway is in the position specified, the person within the cage can transact his business with the cashier who is working at the shelf 50 14. Retrograde rotation of the cage 8 is prevented, due to the cooperation between the back stop pawls 23 and the ratchet wheel 22.

After the customer of the bank has transacted his business, he continues the rotation 55 of the cage 8, by means of the handles 9, until the doorway 10 of the cage again arrives in registration with the doorway 2 of the frame 1, as shown in Figure 1, whereupon the 60 patron of the bank passes out through the registering doorways.

During the rotation of the cage 8, the track 7 on the lower edge of the cage turns in contact with the rollers 6 of Figures 7 and 6, 65 the hollow shaft 15 that supports the cage

turning in the bearing 16 and in the upper spider 8, the head 19 of Figure 3 cooperating with the upper spider 18, to support the cage 8 for rotation. The lamp 25, of course, 70 illuminates the interior of the cage 8.

If the person within the cage 8 attempts to hold up the cashier, or conduct himself in any other way that excites suspicion, the cashier kicks the pedal lever 36 of Figure 8 free from the keeper 38. The spring 33 of Figure 5 then reacts to shove down the latch 26 on top of the member 22, in the path of the stops 27, and the cage cannot be rotated counterclockwise in Figure 4, far enough to bring the doorway 10 of the cage into registration with the doorway 2 of the frame 1, as shown in Figure 1, and thereby let the criminal escape. The back stop pawls 23 cooperate with the ratchet wheel 22 to prevent clockwise rotation of the cage 8, and, as 80 a consequence of all of the foregoing, the criminal remains trapped within the cage.

Although it has been stated hereinbefore that the device is to be used in banks, it will be understood that it may be employed in 90 large manufacturing concerns, or anywhere else, where there is enough money about to tempt a criminal to attempt a hold-up.

What is claimed is:—

In a device of the class described, a frame, a vertical shaft carried by the upper part of the frame, a cylindrical cage disposed within the frame and suspended at its upper end on the lower end of the shaft, the frame and cage having openings which may be brought into registration when the cage is rotated, a circumferential track on the lower end of the cage, supports carried by the frame and spaced circumferentially about the track, 100 rollers carried by the inner ends of the supports and cooperating with the track, the supports being horizontally adjustable in the direction of their length, to effect a centering of the lower end of the cage with respect to the shaft, means for holding the supports in adjusted positions, and means for locking the cage against rotation at the will of an operator without the cage.

In testimony that I claim the foregoing as 115 my own, I have hereto affixed my signature.

MORRIS H. ANDERSON.
